UNITED STATES PATENT OFFICE

ALBERT EDWARD GIBBES, OF SYDNEY, NEW SOUTH WALES, AUSTRALIA

DARNING MECHANISM

Application filed January 9, 1931, Serial No. 507,695, and in Australia January 14, 1930.

This invention relates to improvements in darning mechanism more particularly for repairing silk hosiery and which may be incorporated in a sewing machine of usual construction.

The invention has been devised primarily to provide means whereby the darning may be rapidly effected and whereby the crossed rows of stitches forming the darn may be evenly spaced to effect a neat repair.

According to the invention in its preferred application to an ordinary sewing machine, the table or bed of the machine has a rectangular guide plate secured to it.

On this guide plate there is a carriage provided with means for holding a darning ring which may be of usual construction and in normal operation of the machine is reciprocated transversely over the guide plate by said holding means, the carriage being advanced step by step from left to right or vice versa at the end of each stroke. The extent of travel in each case is under the control of the operator.

The transverse motion of the holder for the darning ring is effected by a screwed shaft mounted in the carriage transversely of the machine. There may be two or more of these shafts having screw threads of different pitch so that a choice of speed is available.

Said shaft or shafts is or are driven say, by the balance wheel of the machine, flexible driving means such as a bowden wire being preferred for this purpose. Suitable toothed gearing is interposed whereby the motion of the holder may be intermittently reversed at will on movement of a lever situated in a convenient position say at the base of the machine head.

Where more than one such shaft is employed there would be a pawl for each pivoted to the holder for the darning ring and adapted to be thrown into engagement with its respective shaft.

The step by step motion of the carriage,

longitudinally of the machine, is effected by a worm mounted for manual rotation by a hand lever, said worm indirectly engaging a rack bar fast to the carriage. Means are associated with said worm to allow of its being thrown out of engagement with the rack bar, when it is desired to move the carriage freely, longitudinally of the machine.

Preferably a darning attachment of the spiral spring type is substituted for the usual presser foot on a sewing machine head, and to prevent the thread from being caught in the shuttle race the bridge piece usually screwed thereto is soldered or otherwise closely secured in position.

But in order that the invention may be clearly comprehended and readily carried into practical effect, reference will now be made to the accompanying drawings wherein:-

Figure 1 is a perspective view showing the application of my invention to a sewing machine head of well known construction, from which the usual feed mechanism has been removed, the usual attachments being indicated in broken lines.

Figure 2 is a plan of the machine illustrated in Figure 1.

Figure 3 is an enlarged perspective view of one form of the holder employed, in accordance with my invention, to receive the darning ring.

Figure 4 is an enlarged plan view of the carriage with its cover removed to reveal the internal mechanism thereof, and showing portion of the guide plate above which the carriage travels.

Figure 5 is a sectional elevation on line 5—5— in Figure 4.

Figure 6 is an enlarged front elevation showing the mechanism for securing longitudinal movement of the carriage and for reversing the traversing motion of the darning ring holder.

Figures 7 and 8 are right and left hand

end elevations respectively of the mechanism seen in Figure 6.

The machine head 9 (Figures 1 and 2) has its base 10 hinged to a wooden bed 11, so that it may be raised in the usual manner for replenishing the bobbin.

It will be seen that the presser foot and feed mechanism of the machine have been dispensed with, in favour of a darning attachment 12 of the spiral spring type, which latter is carried by the needle bar 13.

A guide plate 14 secured to the base 10 has a rail 15 provided at its rear edge to support the rear end of a carriage 16 which is capable of being moved longitudinally over said guide plate.

The front end of the carriage 16 is secured to one end of a shaft 17 on which it is supported. The shaft 17 is slidably mounted in brackets 18 and 19.

There is also a rack bar 20 secured to the carriage 16, alongside the shaft 17, and this passes through a slot 21 in the bracket 18 and is engaged by a spur pinion 22. The pinion 22 and a worm pinion 23 are fast on a shaft 24 as shown more particularly in Figures 1, 2, 6 and 8.

Normally the worm pinion 23 is engaged by a worm 25 on a shaft 26 which is mounted in the brackets 18 and 19 and is capable of being intermittently rotated by a hand lever 27 mounted concentrically upon the shaft 26. When the lever 27 is depressed it partly rotates the shaft 26 and the pinion 28 by means of a pin 127 and ratchet teeth 128 one of which is shown in Figure 6. The pinion 28 meshes with a pinion 29, the function of which will be hereinafter explained. On said lever 27 being released it returns to its normal position under the action of a spring 30.

A leaf spring 31 engaging a square 32 on the end of the shaft 26 serves as a detent for the shaft.

In order to allow of the carriage 16 being moved freely, longitudinally of the machine, the shaft 24 which is provided with a crank handle 34 and the shaft 26 is mounted in a slotted bearing in the bracket 18 and is adapted to be raised and lowered by moving forward a hand lever 33, the upper portion of which is caused to follow the curved face of the upper edge of the bracket 18 and by its forward movement disengage the worm 25 from the worm pinion 23. In this position the carriage 16 may be moved independently of the mechanism under the control of the lever 27, by merely rotating the crank handle 34 in the desired direction.

Referring again to the carriage 16 it will be seen that this is provided with a holder 35 in which a pair of arcuate arms 36 is detachably held by a thumb screw 39. The arms 36 are adapted to embrace a darning ring of well known construction attached in

the usual manner to a stocking or other article to be repaired.

The holder 35 is mounted upon a rack bar 37, Figure 4, slidably carried on a shaft 38 arranged longitudinally in the carriage 16. 70

The rack bar 37 see Figures 4 and 5 is engaged by a worm 40 which is mounted on a spindle one end of which is capable of being raised in its bearings by a hand lever 41 which is pivoted to the carriage 16. The worm 40 75 is also adapted to engage a worm 42 keyed to the shaft 38.

When one end of the spindle of the worm 40 is raised, the worm 40 remains in engagement with the rack bar 37 but is disengaged 80 from the driving worm 42.

The shaft 38 is coupled to a flexible driving shaft 43 whose other end is connected to a spindle 44, (see Figure 2), capable of being reciprocated horizontally in its bearings 45, 85 46 for the purpose of bringing crown wheels 47 and 48 alternately into engagement with a driving pinion 49, the latter being geared, by means of belt 50 which passes over a cone pulley 51, and round a pulley, not shown, 90 on the shaft of an electric motor 52. A separate pulley 53 and belt 54 are provided for driving the usual mechanism of the machine.

Reciprocation of the spindle 44 is effected by a lever 55 whose upper end has a loop 56 95 which fits between two collars 57 on said spindle 44. The lower end of the lever 55 is bifurcated so that it may be oscillated by a cam 58 (Figure 7) which, on each depression of the hand lever 27, is rotated through 100 an angle of 180°.

To facilitate repair of the V shaped portion of "slipper heel" stockings, a triangular graph 59, for use with a pointed 60 may be engraved in the guide plate 14 as shown in 105 Figure 4, the pointer 60 being attached to the holder 35.

In employment of the mechanism illustrated, the stocking or other garment to be repaired is wrapped around a darning ring in the usual manner, with the portion to be repaired disposed approximately in the centre of the ring.

The ring is placed within the arms 36 of the holder 35, and the carriage 16 is moved to the right or left by the handle 34 after first moving forward the lever 33 to disengage the worm 25 from the pinion 23.

When the ring has thus been satisfactorily adjusted beneath the needle bar 13, the machine may be started, when the ring will be moved transversely of the machine in the direction depending on which of the two crown wheels 47 and 48 happens to be in engagement with the driving pinion 49. 120

The length of each row of stitches forming the darn is controlled by the hand lever 27 which when depressed advances the carriage 16 a step and at the same time reverses the motion of the holder 35. 125

After the damaged portion of the garment has been crossed by a plurality of parallel rows of stitches the darning ring is moved within the arms 36 so that a second series of 5 parallel rows of stitches, at right angles to the first, may be added to complete the darn.

It will be readily seen that a triangular darn may be effected by controlling the lever 27 so that the tip of the pointer 60 will not 10 move beyond the boundary of the triangular graph 59.

I claim:

1. Darning mechanism comprising a sewing machine head of the kind referred to, a 15 carriage mounted slidably on the machine bed, a holder for a darning ring supported on the carriage said holder having a rack bar engaged by a pinion rotated by a flexible shaft said shaft being driven by one of a pair 20 of crown wheels capable of being brought alternately into engagement with a driving pinion.

2. Darning mechanism comprising a sewing machine head of the kind referred to, a 25 carriage mounted slidably on the machine bed, a holder for a darning ring supported on the carriage said holder having a rack bar engaged by a pinion rotated by a flexible shaft said shaft being driven by one of a pair 30 of crown wheels capable of being brought alternately into engagement with a driving pinion, and hand operated tooth gearing for advancing the carriage step by step longitudinally of the machine bed and for simultaneously reversing the movement of the rack bar 35 for the holder.

In testimony whereof I have hereunto set my hand.

ALBERT EDWARD GIBBES.
